CLAIM

The ornamental design for a tailgate for an automobile, as shown and described.

DESCRIPTION

FIG. 1 is a perspective view of right, rear, and top of a tailgate for an automobile showing our new design; FIG. 2 is a perspective view of left, rear, and top of thereof; FIG. 3 is a rear view thereof; FIG. 4 is a left side view thereof; FIG. 5 is a right side view thereof; and, FIG. 6 is a top view thereof.

The portions of the tailgate for an automobile shown throughout the drawing views in a deemphasized and faded out half tone form are for environmental and illustrative purposes and form no part of the claimed design.
